UNITED STATES PATENT OFFICE.

WILLIAM M. BAUER, OF CHICAGO, ILLINOIS.

PIANOFORTE AGRAFFE.

Application filed October 23, 1922. Serial No. 596,296.

To all whom it may concern:

Be it known that I, WILLIAM M. BAUER, a citizen of the United States, residing at Chicago, in the county of Cook and State of Illinois, have invented a new and useful Improvement in Pianoforte Agraffes, of which the following is a specification.

My invention relates to an improved construction of the string-bearing provided on the sounding-board bridge in pianos and called an agraffe; and it is fully described and explained in the specification and illustrated in the accompanying drawing, in which—

15 Figure 1 is a broken section taken through the tuning-pin block, sounding-board and hitch-pin plate of a piano, showing my improved agraffe in position on the bridge upon the sounding board and affording bearing for piano-strings;

Figure 2 is an enlarged plan view of the agraffe;

Figure 3 is a section on line 3—3, Fig. 2, but showing a piano-string in the agraffe;

25 Figure 4 is a plan view of the agraffe as represented in Fig. 1, and

Figure 5 is a section on line 5—5, Fig. 3. The agraffe 6 comprises a plurality of flat-sided similar members 7, of the preferred shape illustrated, rigidly secured together in spaced relation to afford spaces between them for passage and confinement of the piano-strings 8. While these mem-

35.bers may be formed of any suitable material, including metal, which however is undesirable principally because of being objected to by piano makers and dealers, I prefer to stamp them out of vulcanite fiber of very strong and non-brittle quality adapt-

40 ed to withstand the strain of the tautened strings. Only as many members need be contained in the agraffe as are required to provide a space between them for each string, thus three spaces, as shown, that be-

45 ing usual for each treble-tone. The shape
of each member 7 involves a substantially
rectangular base-portion from which ex-
tends a curved head 7^a and recessed neck 7^b,
50 adjacent to which is a recessed shoulder-
portion 7^c.

To secure together the plurality of members 7 for producing my agraffe, they are assembled with suitable interposed spacers and secured in their equally-spaced relation by pins 9, passed through their base-portions. These pins should be surface-rough-

ened and preferably threaded to screw through alining openings provided to admit them in the assembled members. For securing the agraffe in place on the bridge 10 of a sounding board 11 (Fig. 1), studs 12, preferably surface-roughened, as represented, are provided to be driven into openings formed to receive them in the bridge. By forming these studs with the flattened perforate heads 12^a shown, the latter may be used for the central spacers in the assembly of members 7, the threaded pins being caused to pass through the perforate stud-heads, and permanently and rigidly securing the studs in place. Other spacers (not shown) that may be employed for maintaining, in the present instance, the outermost of the assembled members in their spaced relation while being secured therein, are thereupon withdrawn.

The agraffe thus constructed has one string-bearing point on the shoulder 7^c, another in the neck 7^b and a third on a pin 13 inserted through the members 7 near the end of the agraffe that is its rear end when 80

the agraffe is in operative position. For the foremost string-bearing, a metal pin 13^a extends across and seats in the recessed shoulders 7^c. A similar intermediate bearing pin 13^b extends across and seats in recesses in the necks 7^b. 85

The piano-strings 8, extending as usual between tuning-pins 14^a on the pin-block 14 and hitch-pins 15^a on the iron plate 15 and passing under a bearing-bar 16 on the block 14 and over an edge-bead 17 on the plate 15, traverse the spaces between the agraffe-forming members in which they bear against the pins 13^a and 13; and before the strings are tautened to hold the bearing-pin 13^a in place, a similar pin 13^b is forced over the strings into the recesses in the necks to give the desired degree of deflection to the strings and cause taughtening of them to confine the pin in place. 90 95 100

I realize that considerable variation is possible in the details of construction herein shown and described and I do not intend to limit my invention thereto except as pointed out in the appended claims, in which it is my intention to claim all the novelty inherent in my invention as broadly as permissible by the state of the art.

I claim:

1. A built-up agraffe comprising a series of separately formed members assembled

and rigidly secured together in side-by-side spaced relation to form string-receiving space between adjacent members, said agraffe having end and intermediate string-bearings.

2. A built-up agraffe comprising a series of separately formed members, and surface-roughened pins extending transversely through the series and rigidly securing the members together in spaced relation, said agraffe having end and intermediate string-bearings.

3. A built-up agraffe comprising a series of separately formed members, pins extending transversely through the series and rigidly securing the members together in

spaced relation, said agraffe having end and intermediate string-bearings, and forward and rear anchoring studs extending from between adjacent members.

20

4. A built-up agraffe comprising a series of separately formed members of vulcanite fiber, threaded pins extending transversely through the series and rigidly securing the members together in spaced relation, said agraffe having opposite-end bearings and an intermediate bearing, and forward and rear anchoring studs provided with flattened heads surrounding said pins between adjacent members.

25

WILLIAM M. BAUER.
